UNITED STATES PATENT OFFICE.

FRIEDRICH STOLL, JR., OF STUTTGART, WÜRTEMBERG, GERMANY.

SOLDERING APPARATUS.

SPECIFICATION forming part of Letters Patent No. 259,598, dated December 6, 1881.

Application filed September 7, 1881. (No model.) Patented in France May 23, 1881, and in England June 25, 1881.

To all whom it may concern:

Be it known that I, FRIEDRICH STOLL, Jr., a subject of the Emperor of Germany, residing at Stuttgart, Kingdom of Würtemberg, 5 Empire of Germany, have invented new and useful Improvements in Soldering Apparatus, of which the following is a specification.

This invention relates to that class of soldering-irons for the use of tinnings, plumbers, and 10 other like workmen, in which vapor generated from liquid hydrocarbon contained in a reservoir forming part of the implement is used as fuel for heating the soldering-head to the required temperature.

15 This class of soldering-irons possesses many advantages over the old method of heating the irons in portable furnaces which are carried from place to place, according to the requirements of the work to be done, as all liability 20 of accidental fires is obviated, and for the further reason that the soldering-head can be kept constantly heated at a high temperature, thus avoiding the inconvenience and delay occasioned in reheating the same.

25 The object of my invention is to produce a soldering-tool which shall be of cheap and simple construction and effective in operation, the arrangement of the parts being such that the heat of the burning hydrocarbon is caused to 30 impinge upon or be carried directly to the soldering-head, thus insuring rapid and perfect heating of the same. This object I attain by the construction and arrangement of parts illustrated in the accompanying drawings, in 35 which—

Figure 1 represents a side elevation of a soldering-tool constructed according to my invention. Fig. 2 is a central vertical section of the same. Fig. 3 is a view of the removable combustion-chamber, showing a modified form of 40 soldering-head; and Fig. 4 is a detached view of a cap or cover for closing the oil-reservoir.

In the drawings, A indicates the hydrocarbon-reservoir, preferably made of metal and 45 conical in form, so that the bottom will form a base for the implement, so that when set in an upright position there will be no danger of its tipping or falling over.

B indicates a metal wick-tube, screw-threaded at one end, which fits into a corresponding thread cut in the top of the reservoir. At the 50 opposite end of the wick-tube is a cock, C, hav-

ing a lever, D, and passage E, by which the flow of vapor to the combustion-chamber may be regulated or shut off entirely, as may be 55 desired.

F is the handle of the implement, secured to the wick-tube which passes through it, and is made of wood or other suitable non-conducting material, so as to prevent injury to the 60 hands by burning.

An ordinary lamp-wick is inserted in the wick-tube, and extends from the cock C down into the reservoir A a sufficient distance to supply the requisite quantity of liquid hydrocarbon to the wick-tube, where it is converted into 65 gas or vapor to be burned in the combustion-chamber.

The combustion-chamber G consists of a metal tube slightly larger in diameter than the 70 wick-tube, so as to fit over the end of the same, as shown, and is provided with air-passages H and igniting-openings I. This tube is open at its outer end, and is formed into or has secured to it two short standards, K K, between which 75 is secured the soldering-head L by means of pivots l, fitting into corresponding holes in the standards.

The soldering-heads are preferably made of copper, and may be of the ordinary hammer 80 shape, as shown in Figs. 1 and 2, or pointed, as shown in Fig. 3.

The tube forming the combustion-chamber may be removed when desired, and the implement used as a lamp for heating or lighting 85 purposes, and when the parts are disconnected from the oil-reservoir the mouth of the latter can be closed by the screw-cap M.

The operation is as follows: The reservoir A being filled with liquid hydrocarbon—such 90 as coal-oil, gasoline, naphtha—and the wick-tube containing an ordinary lamp-wick inserted in the top of the same, the liquid will, by the capillary action of the wick, be drawn up into the upper portion of said wick-tube. The cock 95 C is then closed and the end of the wick-tube heated by an alcohol-lamp or other suitable means for the purpose of converting the liquid into gas or vapor. When sufficient gas or vapor is thus generated the cock is opened and 100 the vapor escapes through the passage E into the combustion-chamber, where it may be ignited through the openings I, and the heat passing out through the top of the chamber

will impinge directly upon the soldering-head and keep it constantly heated at a high and uniform temperature.

What I claim is—

5 The combination of the hydrocarbon-reservoir having a flat bottom adapted to support it in an upright position, the rigid wick-tube B, attached at one end to the mouth of the reservoir, and provided at its other end with a 10 cock, C, for regulating the flow of vapor, the

detachable combustion-chamber secured on the end of the wick-tube and provided with lateral air-openings and an open end, and the soldering-tool connected with the open end of the combustion-chamber, all substantially as 15 shown and described.

F. STOLL, JR.
